UNITED STATES PATENT OFFICE.

EDGAR A. TINSMAN, OF WILLOUGHBY, OHIO, ASSIGNOR TO THE STANDARD TIRE COMPANY, OF WILLOUGHBY, OHIO.

DESIGN FOR A TIRE.

55,142.

Specification for Design.

Patented May 11, 1920.

Application filed January 5, 1920. Serial No. 349,619. Term of patent 14 years.

To all whom it may concern:

Be it known that I, EDGAR A. TINSMAN, a citizen of the United States, residing at Willoughby, in the county of Lake and State of Ohio, have invented a new, original, and ornamental Design for Tires, of which the following is a specification, reference being had to the accompanying drawing, forming part thereof.

The figure is a perspective view of a portion of a tire, showing my new design for a tire.

I claim:

The ornamental design for a tire, as shown.

EDGAR A. TINSMAN.
